United States Patent Office

Des. 188,254

Patented June 21, 1960

188,254

DRAINER BASKET

Kurt E. Christoffersen, East Hampton, Conn., assignor to The Artistic Wire Products Co. of Conn., Incorporated, a corporation of Connecticut

Filed Dec. 28, 1959, Ser. No. 58,829

Term of patent 14 years

(Cl. D44—29)

Fig. 4.

Fig. 1 is a top plan view of a drainer basket embodying my new design.

Fig. 2 is a side elevational view thereof.

Fig. 3 is an end elevational view.

Fig. 4 is a top perspective view thereof.

I claim:

The ornamental design for a drainer basket, substantially as shown.
